UNITED STATES PATENT OFFICE.

HENRY S. MANN, OF CHICAGO, ILLINOIS.

RAIL-JOINT.

SPECIFICATION forming part of Letters Patent No. 769,553, dated September 6, 1904.

Application filed November 20, 1903. Serial No. 181,902. (No model.)

To all whom it may concern:

Be it known that I, HENRY S. MANN, a citizen of the United States, residing at Chicago, in the county of Cook and State of Illinois, have invented new and useful Improvements 5 in Rail-Joints, of which the following is a specification, reference being had to the accompanying drawings, forming a part thereof.

The purpose of this invention is to provide 10 an improved joint for railway-rails and means for locking the nuts especially adapted to such joint.

It consists in the features of construction set out in the claims.

15 In the drawings, Figure 1 is a plan view of a railway-joint embodying my invention. Fig. 2 is an inner side elevation. Fig. 3 is a similar view showing a slight modification of the nut-lock device. Fig. 4 is a section at the 20 line 4 4 on Fig. 1. Fig. 5 is a section at the line 5 5 on Fig. 1. Fig. 6 is an end view of one of the clamping-bolts employed in binding the joint. Fig. 7 is a detail under side view of a portion of the base-plate having a 25 special form of aperture to accommodate and prevent rotation of the bolt shown in Fig. 6.

The rail A is shown of customary construction having the base-flanges A', the vertical web A², and the head or tread A³. For securing 30 two such rails at the joint I provide two tie-plates B and C.

The tie-plate B comprises a base-plate B', which extends under the rails to be joined, lapping their junction and may, if desired, 35 reach from a tie N at one side of the joint to a tie C at the other side. This tie-plate comprises integrally with the base-plate portion B' the portion B², trending back toward the rail at an acute angle to the base-plate, between which and the base-plate portion B' in 40 such acute angle one base-flange A' of the rail is entered and adapted to be clamped. From the inner edge of this portion the tie-plate extends upward, the upstanding portion 45 B³ being wedge-shaped by reason of the slope at the lower edge to fit the upper surface of the rail-flange and at the upper edge to fit the under beveled surface of the rail-head A³ and being preferably hollowed at the inner side 50 facing the vertical web A² of the rail. The

tie-plate C has a portion C' corresponding in form and position to the portion B³ of the tie-plate B—that is, being adapted to fit between the under beveled face of the head of the rail and the upper sloping face of the 55 base-flange of the same—and from the lower edge of this upstanding wedge-shaped portion it extends outward in a broad flange C², corresponding to the part B² of the tie-plate B and overhanging the portion of the base-plate A' of the tie-plate B, at which the latter extends beyond the margin of the base-flange 60 of the rail.

At points corresponding to the bolt-apertures in the rails to be joined the upstanding 65 portions B³ and C' of the tie-plates have suitable bolt-apertures d, and track-bolts D of customary construction are inserted through the bolt-apertures of the tie-plates and rails for joining them. The track-bolts have the 70 customary fins D' at diametrically opposite points under the head to render them at that point non-circular, and the bolt-holes d through the tie-plates are oblong, as seen in Fig. 7, to accommodate these fins and prevent 75 the bolts from rotating while the nuts are being tightened on them.

The angle b between the base-plate B' and the portion B³ of the tie-plate B is formed originally a little sharper than the angle between 80 the upper and lower surfaces of the base-flange of the rail, and when the two tie-plates are applied at opposite sides of the rails to be joined and the track-bolts are drawn up to tighten them the spreading of the angle between the base-plate B' and the portion B³ of the tie-plate B would tend to throw the base-plate away from the under surface of the rail base-flange. This is checked by the clamping-bolts E, which pass through the oblong 85 countersunk holes b' in the base-plate B', being provided with fins e to prevent them from rotating, and take thence through the bolt-apertures in the flange C² of the tie-plate C and receive the nuts F above said flange. 95

The flange C² has at its outer edge a downwardly-projecting lip or bead C³, which when the joint elements are drawn together by tightening the bolts stops on the upper surface of the base-plate B', forming a support 100

outside the line of bolts E, so that as the nuts are further tightened on the bolts E they have opportunity to draw the flange C² toward the base-plate B' and increase the grip which the two tie-plates obtain upon the base-flange, and it is rendered very tight by the wedging of the upstanding portions B³ and C' of the tie-plates between the diverging upper surface of the rail base-flange and under surface of the rail-head, the result of the action of both sets of bolts D and E being to give the tie-plates a very strong grip not only against the opposite sides of the rail by means of the upstanding wedge portions B³ and C', but against the upper and lower surfaces of the base-flange thereof by means of the powerful lever action which the base-plate obtains for gripping the flange, which may be understood by treating the angle b as the fulcrum of said plate operating as a lever and considering that the clamping pressure is applied where the bolt E engages said plate at the opposite side of the rail.

The track-bolts E are put in with the ordinary so-called "staggered" construction—that is, alternate bolts having their heads at opposite sides—so that at each side only alternate bolts show the nuts D². For locking the nuts at the side at which the tie-plate C is applied advantage is taken of the double line of nuts there exposed—to wit, the line of nuts D² on the track-bolts D and the line of nuts F on the clamping-bolts E. This latter line is set at a slight angle to the trend of the rail, as may be seen upon close inspection of Fig. 1, whereon the dotted line X X is the line in which the centers of the bolts would stand if arranged in line parallel with the rail. A key-plate G is provided having a taper corresponding to the deflection of the line of the bolts from the line of the rail, as indicated. This key-plate has a flange G' turned up at one edge to abut against the sides of the nuts D² on the track-bolts, the other edge g abutting against the inner sides of the nuts F on the clamping-bolts E. The key-plate is preferably sprung or curved upward between the edge g and the angle, as seen in Figs. 4 and 5, and said edge g is also preferably slightly beveled, making an acute angle at the lower corner. When the nuts D² and F are tightened, they may be brought to final position, with the lower faces of the nuts D² in line and the inner faces of the nuts F in line, so that the key-plate G being interposed endwise into the angle of the tie-plate C under the nuts D² and inward from the nuts F may be driven tight against the proximate faces of the two rows of nuts, and thus secure them all against turning.

Preferably the tie-plate has several notches G³ G³ toward one end, and the key-plate may be driven to position and the driving be stopped with one of these notches registering the spike-apertures L in the tie-plates,

so that a spike which may be driven to secure the rail and tie-plates to the ties will also secure the key-plate against longitudinal displacement. Spike-apertures L' are formed through both the elements B' and B³ of the tie-plate B at the opposite side, and spikes driven therethrough, as through the apertures L, secure the tie-plates directly to the ties for holding the rails thereto; but it will be noticed that this joint is adapted to be perfectly secure and to constitute a rigid connection between two rails as strong as the rail itself even when such junction occurs between ties, so that the tie-plates are not lodged on the ties at all.

For locking the nuts on the track-bolts D at the outer side opposite that in which the key-plate G is employed I provide a key-plate H. This key-plate is slightly curved transversely to hollow it on the side facing the upstanding element B³ of the tie-plate B and at its upper edge is preferably beveled to an acute angle to give it a slight biting effect on the face of the tie-plate. It has a notch or notches H' of suitable width to stride the shank and pass under the head of the bolt whose head is at that side of the rail, and at its lower edge it has the outwardly-turned flanges or lugs H² H² extending from the margins of the notch H', and thereby projecting out under the edge of the head of the bolt when the latter is drawn up against the outer face of the key-plate when tightening the nut. These lugs or flanges H² thus prevent the escape of the key-plate. When there are only two bolts having the nuts on that side, as in the forms shown in Figs. 1 and 2, this key-plate need not extend farther than to the nuts at opposite sides of the bolt, under whose head it is engaged as described, and at the ends it has then the flanges or lugs H³ H³, which are turned out against these nuts D², as seen in Fig. 2. When there are more than two bolts having nuts at that side of the rail, the key-plate may be made in the form shown in Fig. 3—that is, having two notches H'—to adapt it to stride the shanks of the two bolts whose heads are at that side, having intermediate them a notch H⁴ to stride the intermediate nut D² and having lugs turned out at the opposite edges of the notch, between which the nut is held with the two opposite faces abutting against said two opposite lugs. At the ends of the key-plate in this form there will be formed the lugs M³ M³ to abut, as described, against the faces of the two nuts on the bolts at the ends of the row.

I claim—

1. A rail-joint comprising two plates having similar elements adapted to lodge at opposite sides of the vertical web of the rail between the base-flange and head thereof; one of said plates having rigid with it a base-plate extending under the rail and projecting past the rail-base at the opposite side; the other plate hav-

ing a flange extending off toward the side at which the base-plate projects, and projecting also past the rail-base and overhanging the projecting portion of the base-plate at an interval therefrom; bolts binding the two plates together at opposite sides of the vertical web of the rail, and bolts extending across such interval clamping the base-plate and said horizontal flange toward each other.

2. A rail-joint comprising, in combination with the tie-plate, B, having an upstanding portion for wedging between the base and head of the rail, and integrally therewith a base-plate portion extending under the rail, and the tie-plate, C, having also a portion for engaging between the head and base-flange of the rail and the flange, C², extending off therefrom overhanging the base-plate at an interval, and provided at its outer margin with a downwardly-projecting bead or boss, C³, for stopping on the base-plate; bolts binding said plates together embracing the vertical web of the rail, and bolts clamping the said flange and base-plate together between the margin of the rail and said bead.

3. A rail-joint comprising a base-plate extending under the rail; an element adapted to be rigid with the base-plate at one side and lodged between the head and base-flange of the rail at that side; an element at the other side similarly lodged between the head and base-plate and having a flange extending off beyond the margin of the rail overhanging the base-plate; a row of bolts securing said similarly-lodged elements together embracing the rail; a row of bolts securing the base-plate to said overhanging flange, said two rows of bolts being in slightly-diverging lines; nuts on said bolts and a key-plate tapered to correspond to the divergence of said two lines, entered and wedged between the nuts on the two rows of bolts respectively.

4. A rail-joint comprising a base-plate extending under the rail; an element adapted to be rigid with the base-plate at one side and lodged between the head and base-flange of the rail at that side; an element at the other side similarly lodged between the head and base-plate and having a flange extending off beyond the margin of the rail overhanging the base-plate; a row of bolts securing said similarly-lodged elements together embracing the rail; a row of bolts securing the base-plate to said overhanging flange, the last-mentioned row of bolts being in a line slightly diverging from the trend of the element lodged between the head and base-plate at the side toward the said row of bolts, and a key-plate tapered to correspond to the divergence of said two lines, entered and wedged between the nuts on the two rows of bolts respectively.

5. A rail-joint comprising a base-plate extending under the rail; an element adapted to be rigid with the base-plate at one side and lodged between the head and base-flange of

the rail at that side; an element at the other side similarly lodged between the head and base-plate and having a flange extending off beyond the margin of the rail overhanging the base-plate; a row of bolts securing said similarly-lodged elements together embracing the rail; a row of bolts securing the base-plate to said overhanging flange, the last-mentioned row of bolts being in a line slightly diverging from the trend of the element lodged between the head and base-plate at the side toward the said row of bolts, and a key-plate tapered to correspond with the divergence of said lines having an upturned flange for stopping the nuts on the first row of bolts and adapted at its opposite edge to stop the nuts on the other row.

6. A rail-joint comprising a base-plate extending under the rail; an element adapted to be rigid with the base-plate at one side and lodged between the head and base-flange of the rail at that side; an element at the other side similarly lodged between the head and base-plate and having a flange extending off beyond the margin of the rail overhanging the base-plate; a row of bolts securing said similarly-lodged elements together embracing the rail; a row of bolts securing the base-plate to said overhanging flange, the last-mentioned row of bolts being in a line slightly diverging from the trend of the element lodged between the head and base-plate at the side toward the said row of bolts, and a key-plate tapered to correspond to the divergence of said lines and wedged between the nuts on said two rows of bolts, the plates of said joint having coinciding spike-apertures and the key-plate having a plurality of notches for registering with said spike-apertures.

7. A rail-joint comprising a base-plate for extending under the rail; an element adapted to be rigid therewith at one side, lodged between the head and base-flange of the rail at that side; a similarly-lodged element at the other side having a flange extending off therefrom at the lower edge overhanging the base-plate; and a row of horizontal bolts securing said similarly-lodged elements; a row of vertical bolts securing the base-plate and said overhanging flange, one of said rows being in a line diverging slightly from the plane of the outer face of the elements penetrated by the other row, and a key-plate tapered to correspond to such divergence and adapted to be entered between the nuts on said diverging row and said face from which said row diverges.

8. In a rail-joint in combination with tie-plates embracing the rail between them, bolts which bind the tie-plates to the rail, alternate bolts having their heads at opposite sides of the rail; a key-plate notched to stride the shank of one of the bolts back of the head, having at its lower edge flanges projecting under the lower margin of the head of such

bolt, and having lugs projecting from the face and abutting against the sides of the nuts on the proximate bolts.

9. In a rail-joint in combination with two tie-plates embracing the vertical web of the rail between them; a row of bolts securing said tie-plates together to the rail, alternate bolts in the row having their heads at opposite sides of the rail; a key-plate at one side 5 notched to stride the shanks of the bolts having their heads at that side, and having at the lower edge lugs or flanges projecting under the margin of said heads, said key-plate having also a notch striding the nut of an intermediate bolt, said notch having lugs projecting from its lateral edges, between which the nut is stopped.
10. A rail-joint comprising a base-plate extending under the rail; an element adapted to 10 be rigid with the base-plate at one side and lodged between the head and base-flange of the rail at that side; an element at the other side similarly lodged between the head and base-plate having a flange extending off beyond the margin of the rail overhanging the base-plate; a row of bolts securing said similarly-lodged elements together embracing the rails; a row of bolts securing the base-plate to the said overhanging flange; nuts on the 15 bolts in said two rows, the proximate faces of the nuts in the two rows respectively being in slightly-diverging lines, and a key-plate tapered to correspond to the divergence of

said two lines entered and wedged between the nuts on the two rows of bolts.

11. A rail-joint comprising a base-plate extending under the rail, and an element adapted to be lodged between the head and base-flange of the rail; a row of bolts securing said last-mentioned element to the vertical element of the rail; a row of bolts securing said element to the base-plate, the nuts on said two rows of bolts having their proximate faces in slightly-diverging lines; a key-plate tapered to correspond to the divergence of said lines entered 45 and wedged between the nuts of the two rows.

12. In a rail-joint, in combination with the rails to be joined and the plates for joining them, a row of horizontal bolts securing the joining-plates to the vertical element of the rail; a row of vertical bolts for securing to the horizontal element of the rail, the nuts on the bolts in said two rows having their proximate faces in slightly-diverging lines, and a tapered key-plate entered and wedged between said proximate faces, and means for retaining the key-plate against longitudinal displacement.

In testimony whereof I have hereunto set my hand, in the presence of two witnesses, at 60 Chicago, Illinois, this 11th day of November, A. D. 1903.

HENRY S. MANN.
